(57) **CLAIM**

The ornamental design for a microcontroller assembly housing for a construction kit, as shown and described.

DESCRIPTION

FIG. 1 is a top front perspective view of a microcontroller assembly housing for a construction kit in accordance with the invention;

FIG. 2 is a top rear perspective view of FIG. 1;

FIG. 3 is another top rear perspective view of FIG. 1;

FIG. 4 is a bottom front perspective view of FIG. 1;

FIG. 5 is another bottom front perspective view of FIG. 1;

FIG. 6 is front side view of FIG. 1;

FIG. 7 is a rear side view of FIG. 1;

FIG. 8 is a right side view of FIG. 1;

FIG. 9 is a left side view of FIG. 1;

FIG. 10 is a top side view of FIG. 1; and,

FIG. 11 is a bottom side view of FIG. 1.
